UNITED STATES PATENT OFFICE.

JOHN CONNER, JR., OF CANNONSBURG, AND HENRY A. OTTO, OF ALLEGHENY, PENNSYLVANIA.

WELL-DRILLING MACHINE.

SPECIFICATION forming part of Letters Patent No. 300,222, dated June 10, 1884.

Application filed February 19, 1884. (No model.)

To all whom it may concern:

Be it known that we, JOHN CONNER, Jr., of Cannonsburg, in the county of Washington, and HENRY A. OTTO, of Allegheny, in the county 5 of Allegheny, and State of Pennsylvania, have invented certain new and useful Improvements in Well-Drilling Apparatus; and we do hereby declare that the following is a full, clear, and exact description of the invention, 10 which will enable others skilled in the art to which it appertains to make and use the same, reference being had to the accompanying drawings, which form a part of this specification, in which—

15 Figure 1 is a side elevation from one side. Fig. 2 is a similar elevation from the opposite side, and Fig. 3 is a longitudinal vertical section.

The object of this invention is to provide 20 an apparatus for drilling Artesian and other wells by means of a simple construction which, while cheaply built, shall be efficient and capable of every sort of adjustment to adapt it to any required work.

25 The invention consists in the construction and arrangement of devices, substantially as hereinafter fully described and claimed. In apparatus of this kind now in use we have observed that the mechanism adapted for giving 30 motion to the drilling-tool produced violent jarring of the whole machine, thereby introducing an element of destruction to the mechanism, and rendering it a difficult task to maintain the machine in a steady position while 35 working. Further, in most cases a derrick is used with the machine, and this has always been an independent structure, whose erection and lowering take a great deal of valuable time and labor. Further, it is in most 40 cases a task requiring great watchfulness and manual skill to properly feed the tool as the work progresses. By our invention we have aimed to surmount these difficulties and construct a machine whose every function is under complete control and requires no special 45 skill to operate.

More particularly, our invention is as follows: The apparatus is supported on a rectangular frame, *a a a*, at one end of which the 50 uprights are extended, and form pivotal sup-

ports *b* for a swinging derrick, *c*, at whose top are two sheaves—one, *d*, for the drilling-rope *e*, and the other, *f*, for the sand-pump rope *g*. The foot of the derrick *c*, when vertical, extends below the pivotal line, and the derrick, in lowering, drops backwardly over the machine, while its bottom swings up outwardly away from the machine. Suitable stops and, if desired, locks or latches may be arranged to hold the derrick vertical when at work. 55 The derrick is lowered for more convenience in moving the machine from place to place. For this raising and lowering we arrange in the following manner: In suitable bearings on frame *a*, preferably near its front or derrick end, we journal a winding shaft or reel, *h*, carrying at one end a gear-wheel, *i*, into which meshes the worm *k* of shaft *l*, suitably journaled on frame *a*, and having a hand-wheel, *m*, at the front end of the frame. To 60 the lower extension of the derrick *c* we attach one, or preferably two, ropes or chains, *n*, whose other ends are fixed so as to wind upon the reel *h* or unwind therefrom. When the derrick is in lowered position, as in Fig. 65 1, we have simply to turn the hand-wheel in a direction to wind up the rope or ropes *n*, which then pull the lower extension of derrick *c* downwardly and elevate its main structure. To lower the derrick this operation is 70 reversed. During these movements of the derrick the ropes *e* and *g* will usually remain in position on their respective sheaves. Across the top of the frame *a a* we journal the 75 main drum *A*, upon which is wound a suitable length of the drilling-rope *e*. At the ends outside the frame we place on the shaft *j* of drum *A* the respective gear-wheels *o* and *p*, wheel *o* being keyed to the shaft, and wheel *p* loose, connected to the shaft through the 80 medium of a pawl, *q*, on the wheel *p*, and a ratchet-wheel, *r*, keyed or otherwise fastened to the shaft. While the weight of the tool is 85 on the free end of rope *e*, drum *A* is locked by the worm *s*, which is fixed on a shaft, *t*, suitably journaled to the side of frame *a a*, and extending out to a hand-wheel, *u*, at the front end 90 of said frame. While the drill is operating a slight turn of the hand-wheel *u* rotates the drum *A* and gives the proper feed to the rope, 95 100

and the slightest degree of progressive feed may be thus easily effected, as is obvious. At the back end of the frame *a a* we journal transversely the main driving-shaft *B*, which receives motion by a pulley, *C*, at its center, driven by a belt, *D*, from a steam-engine or other motor, which shaft *B* is in continuous motion while the drilling-machine is in operation. The said shaft revolves in the direction indicated by arrows. By thus placing the main pulley *C* at the center of the end of the machine we at once secure comparative stability, and the machine requires but little staking to preserve it in a fixed position. At 15 that end of shaft *B* corresponding to the position of fixed gear-wheel *o* of drum *A*, we fix a wide pulley, *E*, which by belt *F* gives motion to the fast and loose pulleys *G* and *H*, which are on shaft *I*, which is suitably journaled to frame *a a*, and carries a pinion, *v*, meshing with the said gear-wheel *o*, as shown. The belt *F* is made to run at will on the fast or loose pulley *G* or *H* by means of the shifter *L*, which also extends to the front end of the 20 frame *a a*, as shown. By throwing the shifter *L* till the belt *F* runs on the tight pulley *G*, the revolution of pinion *v* turns the drum *A* and winds up the rope *e*, thereby elevating the tools as far as desired, whereupon the 25 shifter *L* is restored to its original position.

The tools on rope *e* are rapidly lowered into the well in the following manner. Shaft *j* of drum *A* has a friction-wheel, *M*, fixed to it, as shown, and a suitable brake shoe or strap, 30 *w*, of any desired form, is arranged on frame *a a*, so as to be operated by a long hand-lever, *x*, extending to the front of frame *a a*, as shown. Worm-shaft *t* has a slight inclination, as shown, and has a stop-collar, *y*. On frame 35 *a*, or on the boxing of said shaft *t*, we place a swinging latch-block, *z*, arranged to drop over shaft *t* in front of collar *y* when the worm *s* is in full engagement with gear-wheel *p*, and thus prevent its motion forwardly; but by lifting 40 the block *z* shaft *t* slips forwardly and permits the worm *s* to move out of engagement with wheel *p*, whereupon the drum *A* is free to unwind, and the weight of the drilling-tools applies force to the drum, whose tendency to unwind 45 is then readily governed by the brake-lever *x*, so that the tools may be lowered at any desired speed. When they are sufficiently lowered, the brake is used till the hand-wheel *u* is rotated sufficiently for the worm *s* to draw 50 itself into gear with wheel *p*, upon which block *z* is dropped again, and the brake may be released. Across the upper portion of the rear end of frame *a* we journal the sand-pump reel *N*, upon which is wound the sand-pump rope 55 *g*, which proceeds thence directly to and over the sheave *f* on derrick *c*. On the end of main driving-shaft *B* opposite that having pulley *C* we fix a wide pulley, *P*, which is in continuous rotation in the direction indicated 60 by arrow. On the corresponding end of the shaft or journal of the sand-pump reel *N* we

fix a pulley, *O*, and hang a yoke, *Q*, which carries an idler or friction pulley, *R*, and the yoke *Q* is controlled by a rod, *a'*, connected to a bell-crank lever, *b'*, to whose other end we connect a treadle, *c'*, by means of a rod, *d'*. Bell-crank lever *b'* is lifted by a spring, *e'*, so that normally the idler *R* is out of action and the sand-pump may at any time be lowered into the well after the tools have been withdrawn. Upon its reaching bottom the operator places his foot on treadle *c'*, which throws idler *R* between the bite of pulleys *O* and *P*, thus by friction giving motion to the sand-pump reel *N*, which then winds up rope *g* and lifts the sand-pump out of the well. 75

One of the principal features of our invention is the peculiar device for giving the proper rise and fall to the tools. A shaft, *S*, is suitably journaled across frame *a a*, and fixed to this or swinging on it is an L-shaped vibrating lever, *T*, one of whose arms, *f'*, carries a swiveled sheave, *g'*, under which the drilling-rope *e* passes before rising to the derrick-sheave *d*, and the other of whose arms, *h'*, is bifurcated, as shown, and forms a slide or link for the operating crank-pin. A belt, *k'*, from pulley *P* passes to a fast pulley, *l'*, and a loose pulley, *m'*, on a shaft, *n'*, journaled in the frame *a a*. Shaft *n'* also carries a pinion, *p'*, which meshes with a gear-wheel, *V*, on a shaft, *r'*, to which is also fixed a crank-disk, *W*, which carries a crank-pin, *s'*, upon which works the fork *h'* of lever *T*. A shifter, *t'*, extends out to the front end of the apparatus, 90 and when operated to throw belt *k'* onto the fast pulley *l'* the disk *W* is set in rotation in the direction shown by arrows. 95

It will be observed that from the time the pin *s'* is at the right-hand limit of its throw till it rises to the dotted position in Fig. 3 it is depressing the sheave *g'*, and therefore elevating the tools, and from the dotted position down to the said point of starting the sheave *g'* is free to rise and the tools to drop; hence in every revolution of the disk *W* the tools fall in one-fourth the time taken in lifting them, giving an effective blow every time. This is done, too, in an easy and gradual movement without noise and without producing severe shocks to the whole machinery. 110

To prevent undue chafing of rope *e*, we place a friction-sleeve, *v'*, on the central part of shaft *l*, on which rope *e* rides between drum *A* and sheave *g'*. 115

By the foregoing construction all the operations necessary in drilling a well can be quickly and easily effected without jolting or jarring. All the controlling levers and devices are at the front end of the machine within instant 120 reach of the operator. He can feed the drill down at the most limited rate, or rapidly, according to the nature of the rock under the drill. He can instantly stop the rise and fall of the drill, lift it out of the well, lower the sand-pump and take out the sand, drop the drill quickly, and proceed with drilling, and 125

all without moving away from his position at the end of the machine where the well is being drilled.

We claim as our invention—

5 1. In a well-drilling apparatus, the combination, with the frame thereof, of a derrick, *c*, pivoted above its bottom, rope or ropes *n*, attached thereto and to a winding-shaft, *l*, on said frame *a*, gear-wheel *o* on said shaft, a worm, *h*, meshing therewith, and a hand wheel or 10 crank, *m*, substantially as described.

15 2. In a well-drilling apparatus, a drum having the drilling-rope hitched thereto and unwinding by the gravitation of the drilling-tool, and provided with a gear-wheel, in combination with a hand-operated worm, normally locking said drum by engaging with the gear-wheel, but constructed and adapted to be un-gearred and geared therewith at pleasure, substantially as described.

20 3. In a well-drilling apparatus, a winding-drum, *A*, for the drilling-rope, having a gear-wheel, *o*, attached thereto, in combination with the pulley *E* on the main shaft *B*, belt *F*, shaft *I*, having fast and loose pulleys *G H*, and pinion *v*, and a shifter, *L*, for said belt, substantially as described.

25 4. In a well-drilling apparatus, the combination of drum *A*, having ratchet-wheel *r* fixed thereto, loose gear-wheel *p*, having pawl *q*, and

longitudinally-movable worm *s*, substantially as described.

5. In a well-drilling apparatus, a crank-pin, *s'*, rotating in one direction, in combination with a vibrating lever, *T*, controlling the drilling-rope at one end, and at the other straddling the said crank-pin *s*, substantially as described.

35 6. In a well-drilling apparatus, the pivoted lever *T*, having sheave *j'*, adapted to operate the drilling-rope, and fork *h'*, in combination with the crank-pin *s'* on shaft *r'*, and suitable means of rotating said shaft *r'*, substantially as described.

40 7. In a well-drilling apparatus, the pivoted lever *T*, having sheave *j'*, adapted to operate the drilling-rope, and fork *h'*, in combination with the shaft *r'*, having crank-pin *s'*, and gear-wheel *V*, pinion *p'*, shaft *n'*, fast and loose pulley thereon, a belt, *b'*, and driving-pulley *P*, substantially as described.

45 In testimony that we claim the foregoing as our own we have hereto affixed our signatures in presence of two witnesses.

JOHN CONNER, JR.
HENRY A. OTTO.
